Attorney, Agent, or Firm—Roger M. Rickett[57] **CLAIM**

The ornamental design for modular cabinetwork, as shown and described.

DESCRIPTION

FIG. 1 is a perspective view of a modular cabinetwork showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a perspective view of a modified form of the modular cabinetwork shown in FIG. 1, the opposite side being identical thereto;

FIG. 9 is a top plan view thereof; and,

FIG. 10 is a bottom plan view thereof.
